UNITED STATES PATENT OFFICE.

PHILIP ALLEN, OF PROVIDENCE, RHODE ISLAND, ASSIGNOR TO GENERAL FIRE EXTINGUISHER COMPANY, OF NEW YORK, N. Y., A CORPORATION OF NEW YORK.

VALVE.

No. 868,391.

Specification of Letters Patent.

Patented Oct. 15, 1907.

Application filed July 10, 1903. Serial No. 164,988.

To all whom it may concern:

Be it known that I, PHILIP ALLEN, of Providence, in the county of Providence and State of Rhode Island, have invented certain new and useful Improvements in 5 Valves, of which the following is a specification.

The invention relates to that class of valves in which a liquid, usually water, under pressure is held in check by a valve which is held to its seat by the action of a less pressure and is opened upon the reduction of the 10 light pressure. Such valves are especially useful in connection with automatic sprinkler systems in which the water is held in check by a valve closed by the action of a light air pressure in the system and the valve embodying the present invention is especially designed 15 for use in connection with such systems although not confined to such use.

The object of the invention is to provide a valve of this general class which is simple in construction and reliable in action and in which upon the reduction of 20 pressure in the system the valve proper will be fully opened and remain open, thereby insuring the continued and uninterrupted flow of water to the system. This is accomplished by holding the valve closed against 25 pressure by the action of a less pressure and withdrawing the valve to one side of its seat by the action of fluid pressure upon the reduction of pressure in the system and consequent opening or partial opening of the valve.

The construction and arrangement of valve and cooperating means for holding it to its seat by the action of a 30 pressure less than the pressure of the liquid held in check by the valve, and the construction and arrangement of devices for withdrawing the valve to one side of its seat by the action of the fluid pressure when the holding pressure is reduced may be widely varied in embodying the features of the invention in various forms 35 of valve mechanism and I do not intend to limit my invention to the particular construction and arrangement of such devices which is shown in the accompanying drawings and hereinafter specifically described.

40 The various features of the invention will be set forth in the claims and will be better understood from a detailed description of a valve mechanism embodying all such features.

In the drawings in which such a valve mechanism is 45 shown, Figure 1 is a sectional elevation on the line 1—1 Fig. 2, Fig. 2 is a sectional plan view with parts broken away, Fig. 3 is a sectional elevation on the line 3—3 Fig. 2, and Fig. 4 is a similar elevation of a modified construction.

50 In the form of valve mechanism shown in the drawings the valve casing 1 is provided with flanges 3, 3, for connecting the valve with the supply pipe and with a pipe forming a part of the sprinkler system. The inlet passage 4 which forms a continuation of the supply pipe

when the valve is connected with the system, is provided with a valve seat 5 for a valve 6 arranged within the casing. The valve is normally held to the valve seat against the pressure in the supply pipe by the light air pressure in the system. The means for thus holding the valve to its seat in the construction shown in Figs. 55 1, 2 and 3, consist of a movable member in the form of a flexible diaphragm 7 which separates the intermediate chamber 8 from the light pressure chamber 9 which is in communication with the system. The chamber 8 is connected with the atmosphere through a drip opening 10 so that the pressure in said chamber is less than the pressure in the system and light pressure chamber. The pressure upon the upper side of the diaphragm is 60 therefore greater than the pressure on the lower side and the diaphragm is so connected with the valve that this 65 pressure tends to force the valve against the valve seat 5 and by reason of the greater area subjected to the light air pressure the valve is held to its seat against the high pressure in the supply pipe.

In the construction shown the outlet from the chamber 8 is through an opening 11 in the diaphragm 7. The diaphragm 7 is provided with a valve seat 12 surrounding the opening 11 and arranged to be seated upon the upper side of the valve 6 so that the valve 70 serves to normally close the outlet opening 11 and 75 when in normal position forms in effect a part of the movable member which is subjected to the light air pressure in the system. As long as the light air pressure is maintained in the system the pressure upon the 80 movable member holds the valve seats and valve 85 firmly in engagement so that there is no communication between the inlet passage 4 and the intermediate chamber 8 or between the system and the intermediate chamber. When the light air pressure is reduced by 90 the opening of a sprinkler for instance, the pressure in the inlet 4 lifts the valve 6 from the valve seat 5 allowing the water to flow into the chamber 8. When 95 this occurs the valve 6 is withdrawn from between the valve seats 5 and 12 by the pressure of the water upon a movable member connected with the valve. In the construction shown, the movable member, which 100 is subjected to the pressure of the water in the supply pipe when the pressure in the system is reduced and the valve 6 opens, consists of a piston 13 mounted in a cylinder 14 which is connected to the valve casing and communicates with the chamber 8. This piston is connected with the valve by means of a link 15 one end of which is connected to the piston rod 16 and the other end of which is pivotally connected with the valve. When the water flows into the chamber 8 it acts against 105 the inner side of the piston 13 and forces said piston outward in the cylinder 14 thus drawing the valve to one side of the valve seat 5 and from between this valve

seat and the valve seat 12. The outer end of the cylinder 14 is closed and an air vent provided around the piston rod so that an air cushion will be formed back of the piston to prevent too sudden movement thereof when subjected to the pressure of the water in the chamber 8. As the valve is drawn to one side by the action of the water on the piston 13 it is guided and supported in ways 17 provided with guiding slots engaged by ribs 18 on the valve. The ribs 18 fit loosely within the guide ways 17 so that the proper vertical movements of the valve will not be interfered with.

By withdrawing the valve to one side of the valve seat when the pressure in the system is reduced the valve is moved into a position where it will remain open until manually returned to its seat and the communication between the supply pipe and the system will therefore remain open until the valve is again intentionally reseated. By reason of the arrangement of the inlet and outlet opposite each other with a valve arranged between the valve seats at the inlet and outlet and withdrawn from between the valve seats upon the reduction of the pressure in the system, an unobstructed and direct passage for the flow of the water from the supply pipe to the system is provided which is of advantage in insuring a proper and continuous supply of water under all conditions. By employing a movable member subjected to the pressure of the water in the supply pipe when the pressure in the system is reduced for withdrawing the valve a sufficient force is insured for effecting the withdrawal of the valve under all conditions.

After the valve has operated to open the communication between the supply pipe and the system it may be reset in the following manner. The water supply is cut off and the handhole 19 opened by removing the plate 20 so that access to the interior of the valve casing may be had. The valve seats are cleaned and the valve drawn back into position between the valve seats. When in this position the valve seat 12 is pressed lightly against the outer seat of the valve either by reason of the tension of the diaphragm 7 or by the action of a light spring 21 which tends to force the dia-

phragm toward the valve seat 5. The valve is guided between the valve seats as it is moved into position by the ribs 18 and ways 17 and the valve may be somewhat tapered as indicated in Fig. 1 to facilitate the entrance of the valve between the valve seats or the valve may be provided with inclined surfaces at its forward edge to facilitate its passage between the valve seats. When the valve is brought into position between the valve seats the proper pressure is produced in the system after which the water pressure is turned on.

In Fig. 4 a modified form of movable member for separating the intermediate chamber from the system is shown, the movable member in this construction consisting of a piston 7^a fitting within the valve casing and acting in substantially the same manner as the diaphragm 7 shown in Figs. 1-3. In other respects the construction shown in Fig. 4 is the same as that shown in Figs. 1-3 and the mode of operation is the same.

What I claim and desire to secure by Letters Patent is;

1. In a dry-pipe valve, the combination of a valve, a fixed seat for said valve, a movable seat for said valve, between which seats the valve is clamped by the pressure in the system as long as the requisite pressure is maintained, means for withdrawing said valve from between said seats, and means independent of the pressure in the system for holding the movable seat against the valve in resetting the valve and while the pressure in the system is being raised to the requisite point, substantially as described. 65

2. In a dry-pipe valve, the combination of a valve, a fixed seat for said valve, a movable seat for said valve, between which seats the valve is clamped by the pressure in the system as long as the requisite pressure is maintained, means for withdrawing said valve from between said seats, and a spring for holding the movable seat against the valve in resetting the valve and while the pressure in the system is being raised to the required point, substantially 70 as described. 75

In testimony whereof I have affixed my signature, in presence of two witnesses.

PHILIP ALLEN.
